T. LENNOX

METAL BASKET

Filed Dec. 6, 1920

Inventor
Talbot Lennox,

by Orwig & Haagel Attys

UNITED STATES PATENT OFFICE.

TALBOT LENNOX, OF MARSHALLTOWN, IOWA.

METAL BASKET.

Application filed December 6, 1920. Serial No. 428,714.

To all whom it may concern:

Be it known that I, TALBOT LENNOX, a citizen of the United States, and resident of Marshalltown, in the county of Marshall and State of Iowa, have invented a certain new and useful Metal Basket, of which the following is a specification.

The objects of my invention are to provide a metal basket of light weight and great durability, and which may be manufactured almost entirely by automatic machinery and with a minimum of hand work to thereby produce a basket of this character of inexpensive construction.

15 A further object is to provide an improved metallic bottom piece for a metal basket of this character, connected with the basket proper in such a manner as to form a strong, durable and water-tight joint.

20 A further object is to provide an improved handle for metallic baskets, and improved means for connecting same to the basket part.

25 My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a side elevation of a basket embodying my invention.

Figure 2 shows a fragmentary top view of same.

30 Figure 3 shows a vertical sectional view of a part of a basket embodying my invention.

Figure 4 shows an enlarged, detail section, on the line 4—4 of Figure 1, with 40 one of the toothed rope retaining members in open position.

Figure 5 shows an enlarged sectional view on the line 5—5 of Figure 3.

Figure 6 shows an enlarged sectional view 45 on the line 6—6 of Figure 3; and

Figure 7 shows an enlarged sectional view on the line 7—7 of Figure 3.

50 Referring to the accompanying drawings, it will be seen that the body portion of my improved metal basket is formed complete of a single sheet of metal, and on account of the reinforcements hereinafter described I am enabled to employ relatively thin, light and inexpensive metal.

55 The top edge of the basket is formed when

the material is flat, by rolling it in two complete turns 10, with the material of the body portion at 11 directly below the top rim extending downwardly from the central portion of the rim so that the large roll at the top extends inwardly and outwardly from the upright portion of the body portion the same distance. By this arrangement the top, upon which the most strain in a basket of this character falls, is of great 65 strength, and at the same time no extra material in the way of rods for reinforcing same are necessary.

A short distance below the top rib there is 70 an inwardly inclined rounded rib 12, and an outwardly inclined rounded rib 13, which serve to prevent the basket from buckling in a direction which might tend to deflect it from a true circle.

At a point below the rib 13 the material 75 of the body portion inclines downwardly at 14 and inwardly at 15 to a point spaced apart from the center of the basket only a comparatively short distance, and in this part of the body portion ribs 16 are formed, 80 extending from the top portion of the basket to the lower central portion, said ribs being gradually increased in thickness to the lower central edge, thus tending to add strength to the basket in resisting downward and outward strains on the part of the basket which is most subjected to such strains.

At the bottom edge and around the central opening I flatten out all of the ribs in the manner clearly illustrated in Figure 6 90 and indicated by the numeral 17. This arrangement of bending the ribs over will be more clearly understood by reference to Figure 7, which shows the ribs only partly bent over, as shown at 18 in Figure 7, on 95 the line 7—7 of Figure 3, that is to say, adjacent to the part that is wholly flattened out, as shown in Figure 6.

The bottom member comprises a metal disc 19 of comparatively small diameter, and 100 its edges are interlocked with the edges of the part 17 in the manner illustrated in Figure 3 which shows that the bottom member 19 has an upwardly and outwardly extending rib for engaging the interlocking parts to prevent movement of the interlocking part of the basket member inwardly toward the central portion of the bottom portion, and between the interlocking parts I provide a strip or layer of flexible material 105 110

such as asbestos paper 20, which when the parts are bent together and firmly pressed forms a water-tight joint.

Obviously the joint is made very strong 5 on account of the fact that at the part 17 a hook is formed of substantially three layers of the metal of which the body is formed, and after this hook has thus been bent to the position shown in Figure 3 it cannot be- 10 come unbent by the application of any strains to which the basket is ordinarily subjected, such as would be the case if this hook were formed of only a single layer of ma- 15 terial.

In Figure 5, which is taken on the section line 5—5 of Figure 3, I have illustrated 20 that the ribs near the upper portion of the basket are only of very slight thickness and that the thickness of these ribs tapers pro- 25 gressively in increasing ratio down to the section line 7—7 in Figure 3.

I have also provided an improved handle 30 for metal baskets of this character, each of which comprises a metal clip 21 extended over the top rib of the basket and secured thereto by rivets, and having a projecting portion 22 formed on its outer surface to receive a rope 23, which rope is held in position and against longitudinal movement 35 by a rivet 24 passed through the clip 21 and also through the rope. The ends of the rope are connected with each other, and a grip member for the handle is formed as fol- 40 lows:

The numeral 25 indicates a strip of sheet 45 metal having both of its edges toothed at 26. These two toothed edges are bent in- 50 wardly, and then the handle member 25 is bent into tubular form, with the toothed edges extending toward the center. The ends of the rope are placed in this grip portion, and then the two toothed members 26 are pressed downwardly into position with the teeth thereof entering and engaging the 55 ends of the rope. This grip member per- 60 forms the double function of firmly con- 65 necting the ends of the ropes together, and at the same time providing a round, con- 70 venient handle member that is rigid 75 throughout its length and which forms an 80 excellent grip and protects the ends of the 85 rope against wear.

In the manufacture of my improved 90 basket, and by reason of its improved struc- 95

ture, substantially all of it may be made 55 with automatic machinery with a minimum of hand work. Furthermore, the entire basket is made out of sheet metal of much 60 smaller gauge than is ordinarily employed in metal baskets, and at the same time, on account of the reinforcing features, the 65 basket is very strong and durable.

Furthermore, by my improved means for 70 connecting the bottom piece in position, a water-tight joint is provided and at the 75 same time the joint is made strong enough to withstand all of the strains to which these are ordinarily subjected, even though 80 the material is of very light gauge, on ac- 85 count of the great reinforcement occasioned 90 by the overlapping layers of the ribs at the 95 joint.

I claim as my invention:

An improved metal basket comprising a 100 body portion formed of a single sheet of 75 relatively thin metal having formed in its 80 sides and bottom ribs extending from the 85 central portion of the bottom toward the 90 top of the basket, said ribs being tapered 95 from a maximum thickness at the bottom 100 central portion of the basket to a minimum 105 thickness near the upper end of the basket, the ribs at the bottom central portion being 110 pressed laterally and being of such thick- 115 ness that when thus pressed over they will 120 form a comparatively flat top and bottom 125 surfaces parallel with each other and con- 130 taining substantially three thicknesses of 135 metal, the material thus formed at the bot- 140 tom central portion of the body portion be- 145 ing then bent upwardly, then inwardly, 150 then downwardly, and then outwardly, and 155 a circular sheet metal bottom member 160 formed on its periphery with a hook to in- 165 terlock with the corresponding hook of the 170 basket portion and also formed with an up- 175 wardly extended folded rib adjacent to said 180 hook and bent downwardly over the inter- 185 locking hook portions of the two members, 190 the said bottom portion and the sides of the 195 basket adjacent to the bottom portion and 200 the lower part of the interlocking joint be- 205 ing all substantially in the same horizontal 210 plane to permit the basket to rest upon all 215 of said parts on a substantially flat support, 220 for the purposes stated.

Des Moines, Iowa, September 22, 1920.
TALBOT LENNOX.
